FLEXIBLE CONTAINERS

Palle Carstensen, Copenhagen-Virum, Denmark

Application August 15, 1955, Serial No. 528,311

3 Claims. (Cl. 222—92)

The present invention relates to flexible containers for liquid or semi-liquid materials, such as paste. The invention is more particularly concerned with such containers which have a mouthpiece of special shape, adapted for instance for inserting medical paste in cow-teats, by employing a rather long narrow mouthpiece, and adapted generally for medical use such as discharging medicinal materials into the human eyes.

One-piece containers made of tin or like materials and comprising a flexible tubular wall, and a stiff conical end wall, with a long tubular projection providing the mouthpiece, are expensive to manufacture and it is difficult to prevent burrs or fins at the end of the mouthpiece.

It is known to provide a mouthpiece of thermoplastic resin material with a flange to be clamped against the metal container by means of a nut screwed on a tubular projection of said container. Such containers are expensive to manufacture, comprising two parts with screw threads. The parts are assembled manually which requires much time. The nut may loosen on the container, especially when the contents have a lubricating action and become liquid when warm.

It is an object of the invention to provide a container in which the mouthpiece is securely attached to the container proper.

It is another object of the invention to provide a container which is inexpensive to manufacture.

It is also an object of the invention to provide a container in which the mouthpiece engages tightly the container proper.

It is a further object of the invention to provide a container in which the mouthpiece can be kept disinfected.

In the drawings an embodiment of the invention is illustrated by way of example, the figure showing a longitudinal sectional view of a container according to the invention.

In the drawings 1 designates a flexible substantially tubular wall of a container with a substantially conical and stiff end wall 2 provided with a cylindrical outer projection 3 in which is formed a cylindrical bore defining an outlet aperture for the container. The said parts 1-3 are made of metal in the usual way. A long narrow tubular portion 4 is integral with a wider tubular portion 5 and a substantially conical flange 6 to provide a mouthpiece. The flange 6 engages the inner side of end wall 2, and the portion 5 fits tightly in the bore of said projection 3. Outside said projection 3 the mouthpiece is provided with a yieldable lateral projection 7 engaging the outer edge of projection 3. The said mouthpiece is made of yieldable material, such as polyethylene or material with similar properties, so that the flange 6 can engage elastically and tightly the inner side of end wall 2 even when the projection 3 has an incorrect length which may result during manufacture.

The container further comprises a detachable cap 8 of yieldable material, preferably thermoplastic resin material, such as polyethylene or material with similar properties, surrounding the portion 4 and engaging the outer

2

edge of portion 3 so as to prevent soiling of the mouthpiece.

The mouthpiece is inserted from the bottom of the tube before the bottom is sealed. Portion 7 will yield during insertion. Flange 6 will hinder extraction of the mouthpiece. The container with its mouthpiece is disinfected before the container is filled.

The long thin mouthpiece portion 4 may be omitted, the mouthpiece having only a short nozzle, and the cap 10 8 may be shaped correspondingly. There is thus obtained a flexible tube of substantially the usual appearance to be used in the manner of conventional flexible tubes, for instance for tooth paste and cosmetic pastes, such tube preferably having a short cap of elastic resin 15 material for closing tightly the mouthpiece opening.

I claim:

1. A container for dispensing pastes and like materials which comprises a flexible main wall portion defining the body of the container, a stiff inelastic discharge end 20 wall portion provided with a stiff inelastic axial throat extension defining an aperture, and a substantially tubular mouthpiece element extending through said aperture in said throat extension, said mouthpiece element having an axial bore for discharge of material from said container and having a radially-extending flange firmly overlying the interior surface of said end wall and a pre-formed radially-extending portion exteriorly of said stiff throat extension engaging the end of said extension to lock said mouthpiece in said container, said radially-extending pre-formed portion being sufficiently flexible and bendable to conform to the internal diameter of said stiff inelastic extension whereby said mouthpiece may be introduced into said throat from the interior of said container with said radially-extending portion flexing to permit axially outward passage through said throat, but by cooperating action with said flange said pre-formed portion locking said mouthpiece with said inelastic end wall portion and axial throat extension by reason of the resiliency of the mouthpiece portions against the stiff inelastic throat extension, said axial bore including inner and outer bore portions with the inner bore portion being of greater diameter, and a shoulder-defining wall portion connecting the inner surfaces of said bore portions.

2. A container for dispensing pastes and like materials which comprises a flexible metallic main wall portion defining the body of the container, a stiff inelastic metallic conical discharge end wall portion provided with a stiff inelastic axial throat extension defining an aperture and a substantially tubular mouthpiece element of polyethylene 45 extending through said aperture in said throat extension, said mouthpiece element having an axial bore for discharge of material from said container and having a radially-extending conical flange firmly overlying the interior surface of said end wall portion and a pre-formed 50 radially-extending portion exteriorly of said stiff throat extension engaging the end of said extension to lock said mouthpiece in said container, said radially-extending pre-formed portion being sufficiently flexible and bendable to conform to the internal diameter of said stiff inelastic extension whereby said mouthpiece may be introduced into said throat from the interior of said container with said radially-extending portion flexing to permit axially outward passage through said throat, but by cooperating action with said flange said pre-formed portion locking 55 said mouthpiece with said inelastic end wall portion and axial throat extension by reason of the resiliency of the mouthpiece portions against the stiff inelastic throat extension, said axial bore including inner and outer bore portions with the inner bore portion being of greater diameter, and a shoulder-defining wall portion connecting the inner surfaces of said bore portions.

3. A container for dispensing pastes and like materials

which comprises a flexible main wall portion defining the body of the container, a stiff inelastic discharge end wall portion provided with a stiff inelastic axial throat extension defining an aperture, and a substantially tubular mouthpiece element extending through said aperture in said throat extension, said mouthpiece element having an axial bore for discharge of material from said container and having a radially-extending flange firmly overlying the interior surface of said end wall and a pre-formed radially-extending portion exteriorly of said stiff throat extension engaging the end of said extension to lock said mouthpiece in said container, said radially-extending pre-formed portion being sufficiently flexible and bendable to conform to the internal diameter of said stiff inelastic extension whereby said mouthpiece may be introduced into said throat from the interior of said container with said radially-extending portion flexing to permit axially outward passage through said throat, but by cooperating action with said flange said pre-formed portion locking said mouthpiece with said inelastic end wall portion and axial 15

5 10 15 20

piece portions against the stiff inelastic throat extension, said axial bore including inner and outer bore portions with the inner bore portion being of greater diameter, and a shoulder-defining wall portion connecting the inner surfaces of said bore portions, and a cap covering the exposed end of said mouthpiece element and detachably engaging said radially-extending portion of said mouthpiece element.
